UNITED STATES PATENT OFFICE.

THOMAS TARN HUTCHINSON, OF NEWARK, NEW JERSEY.

CIGARETTE.

No. 890,060.

Specification of Letters Patent.

Patented June 9, 1908.

Application filed February 7, 1906. Serial No. 300,016. (Model.)

To all whom it may concern:

Be it known that I, THOMAS TARN HUTCHINSON, a subject of the King of Great Britain, and at the present time a resident of the 5 city of Newark, in the county of Essex and State of New Jersey, have invented certain new and useful Improvements in Cigarettes, of which the following is a specification, reference being had to the accompanying drawings, forming a part hereof.

The improvements to which the invention relates consist in providing cigarettes with peculiarly formed ignition tips whereby each cigarette to which the invention has been 15 applied is adapted to coöperate with an igniting strip formed upon one or more of the inner sides of its containing box or carton to effect the igniting of the end of the cigarette as the latter is withdrawn from its box or 20 carton.

In reducing the improvements to practice, several requisites have been found necessary to a successful and practical embodiment; and chief among these requisites are the provision 25 of means for insuring the contact of the tips with the igniting strip or strips and the provision of means for producing a uniform ignition over the entire end of each cigarette.

To the end of fulfilling these requisites the improvements have been devised and consist, as was stated above, in providing an ignition 30 tip of peculiar form.

It should be stated that the boxes or cartons in which the cigarettes manufactured in accordance with the present invention are packed are arranged to open at one end so that in withdrawing a cigarette, the latter has to be pulled out longitudinally, the igniting strips being located upon one or more of the inner sides near the open end of the box. It is essential that cigarettes put up in this way shall not be packed too tightly, else it will be difficult to withdraw them conveniently, and for this reason when a cigarette is withdrawn the sides of the cigarette do not ordinarily bind closely against the inner sides of the box. It has been found in practice therefore that the ignition tip upon the end of the cigarette, in order to produce the necessary friction in rubbing across the igniting strip as it is withdrawn from the box, should project beyond the periphery of the cigarette to some substantial extent. Moreover, as the sides of the box are flexible and tend to bulge outwardly there is all the more

necessity of providing some such means to insure the ignition of the cigarette as it is being withdrawn. In accordance with the invention therefore the periphery of the tip is 60 made to extend out beyond the periphery of the cigarette so that as the cigarette is withdrawn at least some portion of the periphery of the tip will strike the strip and produce sufficient friction to ignite it. 65

The ignition will spread immediately to all parts of the tip and will cause the end of the cigarette to become uniformly ignited. In order, however, to further insure the uniform ignition of the end of the cigarette, the tip is 70 preferably extended so as to cover the entire end. In this way there is produced upon the end of the cigarette a glowing coal immediately as any part of the tip becomes ignited by contact with the complementary strip 75 upon the box.

The invention will now be described with reference to the accompanying drawings in which,

Figure 1 illustrates in perspective a box 80 of cigarettes manufactured in accordance with the present invention, the delivery end of the box being open and one cigarette being shown in the position in which it leaves the box. Fig. 2 is a perspective view of the 85 cigarette, and Fig. 3 is a longitudinal section through the box.

From the drawings the box will be seen to consist of an outer casing with flat sides *a* and narrow ends *b*, and an inner casing slideable 90 within the outer casing and provided with a cover *d* having a flap *e* which is folded down over the outer ends of the cigarettes when the box is closed. Upon two of the inner sides of the inner casing *c* are igniting strips *f* designed 95 to coöperate with igniting tips *g* upon the inner ends of the cigarettes, presently to be referred to, these strips extending transversely of the box so that as each cigarette is withdrawn from the box the tip *g* must be drawn 100 over and past the strips *f*. Two such strips are preferably provided in order that the tip *g* may be ignited upon opposite sides as a cigarette is withdrawn.

The cigarettes which are indicated by the 105 letter *h* are shown to be of the ordinary type although it will be understood that this invention is applicable to cigars as well as cigarettes; and the term "cigarette" as used throughout the specification and claims will 110 be understood to be a generic term. In the present case the cigarette is of uniform

cross section although it will be understood that the invention is not necessarily limited in its application to such a cigarette but may be applied to a cigar which does not have 5 a uniform cross-section.

- The tip *g* is constructed so that its periphery is greater than the periphery of the maximum cross section of the cigarette. In the 10 present case, the cigarettes being uniform in cross section, the periphery of the tip extends slightly beyond the periphery of the cigarette but to such a substantial extent as to produce the necessary ignition friction when it is drawn across the strip or strips *f*. 15 When any portion of the tip *g* has become ignited the ignition is communicated at once around the entire periphery of the end of the cigarette by the protruding tip and a uniform ignition results.
- 20 In practice it has been found preferable to cover the entire end of the cigarette with the material of the tip so as to produce after the cigarette is withdrawn a glowing coal covering the entire end of the cigarette and in 25 this way to more certainly insure a uniform, thorough and instantaneous ignition of the tobacco. By these means too the ignition of one portion of the tip is more quickly communicated to the rest of the tip and to the tobacco at the end of the cigarette. After the 30 tips have been thus formed and have hardened the ends of the tobacco are embedded in the tip whereby the tobacco becomes ignited simultaneously with the tip, the tip

being severable from the cigarette as soon as 35 the first ash is formed.

The material of the tip itself is compounded of a particular combination of ingredients which will not result in the production of noxious fumes and which have other qualities 40 which particularly adapt the compound for use in this connection. This, however, forms no part of the present invention, the scope of which is set forth in the following claims.

45 I claim as my invention:—

A cigarette having an approximately uniform cross-section throughout and provided at one end with an ignition disk extending entirely around the same and projecting sufficiently at the sides so as to extend beyond the maximum periphery of the cigarette and covering the entire end of the cigarette, whereby in withdrawing the cigarette from a box provided with an igniting strip upon its inner 50 surface and adjacent its open end, some portion of the ignition disk will strike the igniting strip causing the ignition of the whole disk and simultaneously the ignition of the end of the cigarette.

60 Signed at the city and district of Montreal, in the Province of Quebec, in the Dominion of Canada, this fifth day of February, 1906.

THOMAS TARN HUTCHINSON.
